(57) CLAIM

The ornamental design for a flashlight, as shown and described.

DESCRIPTION

In a preferred embodiment, the nature of this product is as a hand-held flashlight for illuminating objects in the dark. FIG. 1 is a right, top, front perspective view of a flashlight embodying our new design;

FIG. 2 is a right side elevational view thereof, the left side elevational view thereof being a mirror image of the right side elevational view shown;

FIG. 3 is a top plan view thereof;

FIG. 4 is a bottom plan view thereof;

FIG. 5 is a front elevational view thereof; and,

FIG. 6 is a rear elevational view thereof.

The broken line representations in the figures are for the purpose of illustration only and form no part of the claimed design.
